J. R. PEIFER.

FAN BLOWER.

APPLICATION FILED DEC. 11, 1915.

1,186,826.

Patented June 13, 1916.

UNITED STATES PATENT OFFICE.

JAMES ROBERT PEIFER, OF SHEPPTON, PENNSYLVANIA.

FAN-BLOWER.

1,186,826.

Specification of Letters Patent. Patented June 13, 1916.

Application filed December 11, 1915. Serial No. 66,392.

To all whom it may concern:

Be it known that I, JAMES ROBERT PEIFER, a citizen of the United States, residing at Sheppton, in the county of Schuylkill and State of Pennsylvania, have invented certain new and useful Improvements in Fan-Blowers; and I do hereby declare the following to be a full, clear, and exact description of the invention, such as will enable others skilled in the art to which it appertains to make and use the same.

My invention relates to new and useful improvements in fan blowers and my object is to provide a fan and means to operate the same and assemble the casings around the parts whereby the structure will occupy but a minimum amount of space.

A further object is to provide a vent for the admission of air into the fan housing.

A further object is to provide means for attaching the blower to parts of a stove.

A further object is to provide means for conveying the air from the fan housing to a point below the grate in the fire box. And a further object is to provide means for covering the openings in the air conveying means whereby ashes and the like will be excluded therefrom.

Other objects and advantages will be hereinafter set forth and more particularly pointed out in the accompanying specification.

In the accompanying drawings which are made a part of this application, Figure 1 is a sectional view through a heating stove, showing my improved fan mechanism attached thereto. Fig. 2 is an end elevation of the fan mechanism removed from the stove. Fig. 3 is a plan view of the pipe employed for conveying the air to a point below the grate, and Fig. 4 is an enlarged transverse sectional view thereof.

Referring to the drawings in which similar reference numerals designate corresponding parts throughout the several views, 1 indicates a stove which may be constructed in the usual or any preferred manner employed for heating or cooking purposes, 2 indicates the fire box and 3 the grate therein.

Secured at any suitable point to the wall of the stove and preferably in the rear thereof is my improved form of fan construction comprising a housing 4, the outer wall 5 of which is removably secured to the remaining portion of the housing, said wall being held in position by introducing bolts

6 through the inner wall and threading the ends thereof into fillets 7 on the inner face of the outer wall. Rotatably mounted in bearings 8 at the axial center of the housing 60 is a shaft 9 to which is attached a fan 10, said shaft extending through and beyond the outer wall 5 and has a pinion 11 fixed thereon with which meshes a driving gear 12, said driving gear being likewise mounted 65 upon a shaft 13 one end of which finds a bearing in the outer wall 5, while the opposite end projects through the wall of an auxiliary casing 14, the extreme outer end of the shaft 13 having a crank 15 attached 70 thereto by means of which rotating motion is imparted to the driving gear.

The auxiliary casing 14 comprises a circular plate 16, the peripheral edge of which is provided with the flange 17 which projects at right angles to the circular plate, the lower portion of said flange resting against the face of the outer wall 5, while the upper portion projects above the housing 4 and telescopes with a flange 18 80 of a semicircular plate 19, said semicircular plate having a flange 20 at its inner edge which rests upon the edge wall of the housing 4 and is secured thereto in any preferred manner, said housing and casing forming a 85 complete covering for the fan and gears and by arranging the gears in the manner shown, the fan construction may be assembled in compact formation.

In order to admit air into the housing 4, 90 an opening 21 is formed through the outer wall 5 which opening is substantially crescent shape and is positioned immediately below the edge of the auxiliary casing 14 so that the air will be admitted to the fan 95 at a point adjacent its axial center. The housing 4 is provided with an integral nozzle 22 which is preferably positioned below the housing and has connected to its lower end a pipe 23, the coupling 24 employed for securing the pipe to the nozzle being so constructed that said pipe may 100 swivel in the coupling and be directed at various angles as occasion may require.

The pipe 23 is preferably directed at right 105 angles to the vertical trend of the housing and is adapted to be introduced into the stove at a point below the fire grate, the upper portion of said pipe having a plurality of ports 25 therethrough through which the air escapes and by placing said ports in the upper face of the pipe the blast of air will 110

be directed through the grate and into direct contact with the fuel resting thereon.

In order to prevent ashes, or the like, from entering the ports 25 as the ash is shaken from the grate 3, a shield 26 is positioned over the face of the pipe 23, said shield being in the arc of a circle and fitting the outer periphery of the pipe, transverse slots 27 being formed in the shield adjacent its ends through which project studs 28 carried by the pipe 23 and by means of which the rotating movement of the shield upon the pipe is limited. The movement of the shield is regulated by means of a lever 29 which is preferably formed integral with one end of the shield and projects exteriorly of the wall of the stove so that the lever may be readily grasped to swing the shield to a position to cover or uncover the ports, the weight of the shield serving to hold the same against casual rotation.

The prime object of my invention is to provide a blast of air to increase the heating capacity of the fuel within the fire box so that the temperature within the stove may be greatly increased in a very short period of time and the device is further applicable for causing the fuel to readily ignite when the fire is first started and by introducing the pipe into the ash receiving compartment of the stove immediately below the grate on which the fuel is resting these results will be readily accomplished.

When a blast of air is to be directed through the grate and into contact with the fuel, the lever 29 is depressed, thereby rotating the shield 26 around the pipe 23 the full length of the slots 27 and thus uncovering the ports 25. The crank 15 is then rotated which will operate the fan 10 and force the air through the pipe 23 and ports 25, and in view of the fact that the opening 21 is placed adjacent the axial center of the fan a suction will be caused within the housing 4 when the fan is rotated and a constant supply of air drawn into the housing.

As soon as the temperature within the stove has been raised to the proper degree by means of the forced draft, the shield 26 is rotated in the opposite direction through the medium of the lever 29 and the ports 25

covered over so that the ashes falling from the fire box will be prevented from entering the ports 25 and clogging the interior of the pipe 23.

Having thus fully described my invention what I claim as new and desire to secure by Letters Patent of the United States, is:—

1. In a fan blower for stoves, furnaces and the like, the combination with a housing having a discharge nozzle, a fan mounted in said housing, and means to operate said fan to direct a blast of air through the nozzle, of a pipe swivelly connected to said nozzle for adjusting the angular relation of said pipe relative to said nozzle, said pipe having a plurality of ports therein, a curved solid shield embracing the upper surface of said pipe and having transverse slots therein adjacent its ends, studs extending through said slots and into the pipe for limiting the adjustment of said shield, and a lever connected to said shield by means of which the shield may be moved to position to cover or uncover said ports.

2. A blower for stoves, furnaces and the like, comprising a housing having a removable outer wall, said outer wall having an air receiving opening therethrough, a shaft rotatably mounted in said housing, a fan carried by said shaft, a pinion fixed to said shaft, a driving gear meshing with said pinion, an auxiliary casing surrounding said driving gear and pinion, said casing comprising a circular plate having an angularly extending flange at the peripheral edge thereof, a semicircular plate having a flange thereon adapted to telescope with the flange of the first plate, means to connect said plates together and to said housing, a crank for operating said driving gear for revolving said fan, and means to convey the blast of air created by said fan to points beneath a grate.

In testimony whereof I have signed my name to this specification in the presence of two subscribing witnesses.

JAMES ROBERT PEIFER.
